UNITED STATES PATENT OFFICE

2,031,211

ELECTRICAL RESISTANCE DEVICE

Willy Dumke, Chicago, Ill., assignor to Utah Radio Products Company, Chicago, Ill., a corporation of Illinois

Application July 9, 1932, Serial No. 621,668

10 Claims. (Cl. 201—55)

The invention relates to electrical resistance devices and more particularly of the type wherein the resistance is variable.

An object of the invention is to provide a new and improved device in which all of the non-cooperating operative parts are completely insulated from each other and from the supporting structure.

Another object is to provide a device embodying two parts which are relatively movable for varying resistance through infinitesimal steps and having a flexible contact member of novel construction interposed therebetween for preventing wear on the resistance element or distortion of the resistance curve.

A further object resides in the provision of such a flexible contact member which is electrically independent of the resistance element at all times except at one point which may be optionally varied throughout the entire range of said element.

More specifically stated, an object is to provide a resistance element of cylindrical shape having the exposed surface of the resistance element inwardly presented and opposed by a flexible member which is maintained normally in insulated and spaced relation and which is capable of being variably contacted with the exposed surface, said parts having a novel arrangement which facilitates the connections thereof with the required terminals.

Another object is to provide a novel flexible contact member for a resistance element of this nature.

Other objects and advantages will become apparent in the following description and from the accompanying drawing, in which:

Figure 1 is an open face view of a device embodying the features of the invention.

Fig. 2 is a sectional view through a portion of the device taken as indicated by the line 2—2 of Fig. 3, parts being broken away to clarify the illustration.

Fig. 3 is a central section through the device on the line 3—3 of Fig. 1.

Fig. 4 is an elevation of the interior of the device looking at the terminal assembly, parts being omitted for better disclosure.

Fig. 5 is a fragmentary sectional view on an enlarged scale taken through one side of the device.

Fig. 6 is a fragmentary plan view on a reduced scale of the flexible contact member before it is shaped for assembly in the device.

While the invention is susceptible of various modifications and alternative constructions, I

have shown in the drawing and will herein describe in detail the preferred embodiment, but it is to be understood that I do not thereby intend to limit the invention to the specific form disclosed, but intend to cover all modifications and alternative constructions falling within the spirit and scope of the invention as expressed in the appended claims.

Referring to the drawing, wherein the preferred embodiment of the invention is shown merely for the purpose of illustration, 18 designates generally an enclosing case or housing which is preferably formed of sheet metal for economy in manufacture. The case is cup-shaped and comprises a base 11 and a substantially cylindrical side wall 12 defining an open face which is normally closed by a suitable cover 12a (Fig. 3) which is held in place by tabs 13. The base is apertured as at 14 (Fig. 4) to receive a bushing 15 (Fig. 3) of conventional construction within which is journaled a shaft 16 arranged to be rotated by a well-known type of knob or finger piece 17. The shaft 16 supports a presser assembly, generally indicated at 18, the purpose of which will be herein-after more fully described.

Adjacent the inner surface of the side wall 12 is a sheet 19 of any suitable insulating material, which preferably covers the entire wall surface. A flat annular ring or washer 20, also of insulating material, covers a substantial portion of the base of the case inwardly of said wall. An annular cylindrically shaped resistor 21 is disposed concentrically and interiorly of the sheet of insulating material 19 but does not extend completely through the length of the inner periphery 30 of the case. While any suitable type of resistor may be employed, that which is preferred comprises a smooth surface resistor element 22 (Fig. 5) of graphite or like material mounted on or carried by a somewhat flexible base of a phenol 40 condensation product 23 or similar material. The exposed surface of the resistor element is arranged to face inwardly of the case.

In order to avoid injury of the resistor element by the relatively movable contact usually employed, a flexible contact member is provided in interposed relation between the presser assembly and the resistor element. With particular reference to Figs. 4, 5 and 6, a preferred form of contact member comprises an elongated strip 24 of thin, flexible, current conducting material, such as bronze, which strip is disposed within and adjacent to the exposed surface of the resistor element 22.

The flexible strip 24 is preferably maintained 55

in definitely spaced and concentric relationship to the resistor element in the following manner (see Fig. 6). From one side of the strip relatively narrow webs 25 extend, each of which terminates in a flat plate 26. The strip 24, webs 25 and plates 26 are dimensioned so that, by bending the webs along a longitudinal line, generally indicated by the line A—A in Fig. 6, adjacent the plates, a structure of generally U-shaped cross section may be obtained which will fit about or straddle the inner side edge of the resistor 21. Thus, the strip 24 may be maintained in definitely spaced relationship to the resistor element 22 by means of the webs and plates which are bound between the resistor 21 and the insulating sheet 19 and ring 20. The plates 26 preferably have a relatively large surface area to securely hold the strip 24 in place and, while the plates might be formed as a continuous strip, it is preferred to employ plates so that the U-shaped structure may most readily follow the curvature of the case.

As may be seen in Fig. 5, the resistor element 22 preferably stops short, as indicated at 27, of the inner side edge of the resistor 21 to insulate the resistor element from the contact strip. Preferably, an annular relatively narrow ring 28 of insulating material is interposed between the webs 25 and the resistor element 21 adjacent the inner portion of the element. This ring definitely maintains the spaced relationship between the strip 24 and the resistor element.

The presser assembly 18 embodies a flat plate 29 which is rigidly secured to the shaft 16 for rotation therewith. The plate extends radially of the shaft to a point substantially adjacent to the contact strip 24 and is there provided with an outwardly urged presser shoe 30. The shoe carries a tip 31 of insulating material which engages the contact strip 24 and presses said strip into engagement with the underlying surface of the resistor element 22 as shown in Figs. 1 and 3. The point of contact between the strip and resistor element may, therefore, be varied by infinitesimal degrees or steps throughout the entire length of the resistor by manipulation of the knob 17.

As has been mentioned, the resistor does not completely encircle the interior of the case and a terminal 32 is provided for each end of the resistor. These terminals comprise flat plates 33 (Fig. 4) arranged to overlie and contact the surface of the resistor element 22 at the ends of the resistor and have angularly extending contact fingers 34 (Figs. 1 and 2) which extend through small slots 35 in the insulating sheet 19 and an elongated slot 36 in the case wall 12. A third terminal 37 of somewhat similar construction is interposed between the two resistor terminals 32 and is electrically insulated from said terminals between the ends 38 (Fig. 2) of the resistor, which ends extend beyond the terminals 32 to position the back side thereof in overlying relation to the terminal 37.

Both ends of the contact strip 24 are preferably connected to the third terminal 37. This may be accomplished in a simple manner by forming tabs 39 (Fig. 6) to extend longitudinally from the contact element and preferably from the two extreme end plates 26. These tabs 39 are, in assembly, disposed between the insulating sheet 19 and the back side of the resistor 21, as shown in Fig. 2, and extend into electrical contact with the third terminal 37 (Fig. 4).

The assembly of the entire resistor structure

within the case and the electrical connections with the several terminals may be effected and maintained by a single, insulated, securing means. Thus, as shown in Fig. 4, the middle terminal 37 has an enlarged central aperture or recess 40 formed therein and the wall of the case, together with the insulating sheet 19 opposite this recess, is apertured, as at 41, to receive a screw 42 (Figs. 1, 2 and 3) which extends into screw threaded engagement with an arcuate plate 43. The plate 43 extends laterally to overlie both of the outer terminals 32 and a sheet of insulation 44 is interposed between the plate and the terminals. As is shown clearly in Fig. 4, the recess 40 is considerably larger than the screw to prevent short circuiting of the terminal 37 through the screw. Thus, by the screw 42 and plate 43, the terminals 32 may be drawn tightly into electrical contact with the underlying ends of the resistor 21 thereby pressing the back side of each end of the resistor against the opposite sides of the middle terminal 37 to bind the tabs 39 against the terminal 37.

It will be seen from the foregoing description that a device has been provided wherein the case is completely insulated from every current conducting part of the device and that the contact strip and resistor are also insulated from each other, excepting only the single, variable point of contact established by the presser assembly 18. It should be noted that the presser assembly and the rotating shaft therefor are electrically independent of the current carrying elements. Hence, the device is capable of carrying an exceedingly heavy overload of current without danger. A further important advantage is that the enclosing metallic case and cover, which are electrically independent of all circuits, provide a static shield about the device to suppress or eliminate interference. The preferred manner of mounting the contact element in place and of maintaining said element in definitely spaced relation to the resistor facilitates assembly of these parts and results in a structure which is inherently sturdy.

I claim as my invention:

1. An electrical resistance device comprising, in combination, a cylindrically shaped insulator having a resistance element on the inner periphery thereof, an annular contact member disposed in opposition to the inner exposed face of said resistance element, an insulating strip extending along the length of said contact member between a part of said member and the face of said resistance element to normally maintain said contact member from end to end in radially spaced relation to said resistance element, said contact member being movable radially into contact with said element, and means movable circumferentially relative to said insulator and cooperating with the part of said contact member which is free of said insulating strip for moving said part into engagement with said element at variable points along the length thereof.

2. An electrical resistance device comprising in combination, a cylindrically shaped insulator having a resistance element on the inner periphery thereof, an annular contact member disposed in opposition to the inner exposed face of said resistance element, means disposed at spaced points longitudinally of said member for maintaining said member normally in radially spaced relation to said element, said contact member being movable radially outward into contact with said element, means movable circumferen-

tially relative to said insulator and cooperating with said contact member for moving said member into engagement with said element at variable points along the length thereof, and means for connecting said device in an electrical circuit including a separate terminal electrically connected with said contact member.

3. An electrical resistance device comprising, in combination, a cylindrically shaped insulator having a resistance element on the inner periphery thereof, an annular contact member disposed in opposition to the inner exposed face of said resistance element and normally maintained in radially spaced relation thereto, said contact member being movable radially into contact with said element, means movable circumferentially relative to said insulator and cooperating with said contact member for moving said member into engagement with said element at variable points along the length thereof, and means interposed between a part of said contact member and said element and extending substantially along the length thereof for normally spacing the one from the other.

25 4. An electrical resistance device comprising, in combination, a cylindrically shaped element presenting an inwardly facing resistor, an annular flexible contact member within said element and concentrically disposed with respect to said resistor, a substantially coextensive insulating strip interposed between a portion of said member and said element for normally maintaining a definite spaced relationship between said parts, and movable means engaging and pressing said flexible member against said resistor at a variable point.

5. An electrical resistance device having, in combination, a resistor, an element movable across the face of the resistor, and a contact member interposed between said parts including a strip of U-shaped cross section arranged to straddle one side edge of the resistor and having one portion disposed adjacent to the surface of the resistor between said resistor and element and a supporting portion positioned opposite the other face of the resistor for supporting the first mentioned portion in normally spaced relation to said resistor.

6. An electrical resistance device comprising, in combination, a case having a cylindrical side wall, a resistor mounted within said side wall and facing inwardly of the case, means for insulating said resistor from said case, a contact member disposed in substantially coextensive and normally spaced relation to said resistor and including a supporting part held between said resistor and the case, means for insulating said contact member from the resistor and the case, and presser means supported on said case for engagement with said contact member and movable to effect a variable contact of said contact member and said resistor.

7. An electrical resistance device comprising, in combination, a case having a cylindrical side wall, a resistor mounted within said side wall and facing inwardly of the case, means for insulating said resistor from said case, a contact element disposed in substantially coextensive and normally spaced relation to said resistor and including a supporting part extending between the opposite side of the resistor and the side wall, means for insulating said contact element from the resistor and the case, and rotatable means journaled on the case and engaging said contact member to press the member into contact with the resistor at variable points.

8. An electrical resistance device comprising, in combination, a case having a cylindrical side wall, a cylindrical insulating base having a smooth surfaced resistor disposed on the inner periphery thereof and dimensioned to fit within the case, a contact member of generally U-shape cross section arranged to fit about the inner side edge of said base and including a continuous contact strip adjacent to and substantially coextensive with said resistor, insulating means separating the contact member from said case and said resistor, a terminal connected with each end of said resistor, a separate terminal connected with both ends of said contact member, and means for variably pressing said contact strip against the resistor.

9. An electrical resistance device comprising, in combination, a case having a cylindrical side wall, a cylindrical insulating base having a smooth surfaced resistor disposed on the inner periphery thereof and dimensioned to fit within the side wall, insulating means between the resistor and the case, a contact member of generally U-shape cross section arranged to fit about the inner side edge of said base and including a continuous contact strip adjacent to and substantially coextensive with said resistor, insulating means separating the contact member from said resistor, insulated means for variably pressing said contact strip against the resistor, spaced terminals disposed one at each end of the resistor beyond the ends of the contact strip and in overlying relation to the resistor, a third terminal positioned intermediate the first mentioned terminals, said contact member having an extension at each end behind the base for connection with said third terminal, and insulated means for securing said parts in place.

10. A flexible contact member for an electrical resistance device of the character described comprising, in combination, an elongated strip constituting the contacting part of the member, a plurality of separate elements for support of the contacting part in assembly, and connections intermediate said elements and strip adapted for bending to provide a structure of generally U-shaped cross section.

WILLY DUMKE.
